[57] CLAIM

The ornamental design for a trailer booth, as shown.

DESCRIPTION

FIG. 1 is a right rear perspective view of a trailer booth having a raised framework for supporting an awning (not shown) showing my new design;

FIG. 2 is a front elevational view thereof;

FIG. 3 is a rear elevational view thereof;

FIG. 4 is a right elevational view thereof;

FIG. 5 is a left elevational view thereof;

FIG. 6 is a top plan view thereof; and,

FIG. 7 is a left rear perspective view thereof, showing the framework for supporting an awning (not shown) in a lowered position.

FIG. 1

FIG. 4

FIG. 5

FIG. 2

FIG. 3

FIG. 6

FIG. 7
